UNITED STATES PATENT OFFICE.

ROBERT MEYER, OF MÜLHEIM-ON-THE-RUHR, GERMANY.

ROCK MACHINE-DRILL FOR OPERATING WITH FLUSHING-WATER.

1,221,469.

Specification of Letters Patent. Patented Apr. 3, 1917.

Application filed June 5, 1912. Serial No. 701,935.

To all whom it may concern:

Be it known that I, ROBERT MEYER, a citizen of the German Empire, and resident of Mülheim-on-the-Ruhr, Germany, have invented certain new and useful Improvements in Rock Machine-Drills for Operating with Flushing-Water, of which the following is a specification.

My invention relates to a rock machine 10 drill for operating with flushing water.

Known rock machine-drills operating by percussion and with flushing water, in which drills the flushing water is introduced into the bore through the hollow drill either alone 15 or with the aid of the compressed air operating the piston, have fundamental disadvantages. In the machine-drills into whose bores the flushing water is introduced under pressure, from the rear or from the side of the 20 appliance, the parts wherat the water enters are not readily kept tight; moreover, water having a sufficiently high pressure is usually not available. Consequently it has generally been arranged to force the flushing water 25 through the drill and its outlet by means of compressed air. In known machines of this kind which flush with the aid of the compressed air already in the cylinder, the pressure operating the drill is so variable that 30 the flushing is not always satisfactory and a leakage of the flushing water into the machine cannot with certainty be avoided.

A primary object of my invention is to ob- 35 viate these defects, and I consequently ar- range that a pressure, which operates con- tinuously, is produced behind the drill by means of compressed air which is intro- duced independently of that required for 40 the piston; so that the flushing water is al- ways driven at the required velocity through the drill and a leakage of the same into the machine is avoided. The compressed air thus aiding the flushing water is preferably introduced from the rear end of the ma- 45 chine and by means of a pipe concentric with the flushing water pipe and kept air- tight therefrom. The bore of the piston can be made of such a size that the com- pressed air aiding the flushing water, in 50 the event of a larger pressure injurious to the action of the machine arising, can escape through the piston and pass out through an exhaust port.

The air supply for the oscillation of the piston can consequently be kept quite inde- 55 pendent throughout by providing the piston, as is already known in steam engines, with a rear piston-rod, which goes through the cylinder cover and is made suitably air- tight thereat.

The compressed air flowing in the direc- 60 tion of the stream of water gives, owing to its kinetic energy, an effectual impulse to the flushing water in the direction of the pipe. In order to prevent a leakage of the 65 flushing water into the machine the pipe conveying the former to the bore in the drill extends beyond the air pipe. There then obtains in the space into which both pipes project a zone, behind the place where 70 the water issues, which continually remains under air pressure and which prevents a leakage of the flushing water into the machine. The ends of the pipes can be formed like nozzles in order to accentuate the ac- 75 tion in the direction of the drill.

Two illustrative embodiments of my in- 80 vention are represented by way of example in the accompanying drawing, wherein:—

Figure 1 is a longitudinal section of the 80 machine portion of the first form of flush- ing device, which in no way affects the dis- tribution of the compressed air used in the interior of the machine or forms a connec- 85 tion with the air contained in the working cylinder; and

Fig. 2 is a similar longitudinal section of 90 the second form, in which the double feed pipes are used in a percussion machine-drill of normal construction.

Referring to the first form shown in Fig. 1 the piston *b* which is moved to and fro in the working cylinder *a* by the driving agent, for example compressed air, is provided in known manner with a piston-rod *c*, which 95 gives the percussion blows to the projecting end *e* on the drill. The other side of the pis- ton is provided with a rod *d* which passes through the cylinder cover *f* and is rendered air-tight thereat. The cover *f* has a cylin- drical projection *g* into whose end *h* two 100 pipes *i*, *k*, the one fitting into the other with play, are arranged, and in such a way that the interior of the pipe *k* opens into the cham- 105 ber *A* and the interior of the pipe *i* into the chamber *B*. These pipes are made suitably

tight at their bearing places so that there can be no connection between the chambers A, B, C. The piston is provided with a bore i , throughout its length, which bore is 5 of such a size that the pipe k passing through this bore does not come into contact with the same. The front ends of the pipes k , i fit with play into the bore m of a drill arranged in known manner in the machine. 10 The inner pipe i preferably extends somewhat beyond the pipe k . The remainder of the machine is so arranged that the inwardly projecting end e of the drill when returning toward the interior of the machine cannot 15 come into contact with the ends of the pipes i , k . In drills having a small bore the introduction of these pipes is facilitated by widening out the entrance to the bore as shown in Fig. 1. The flushing device operates in 20 the following manner. The pressure water is introduced into the chamber B and flows through the inner pipe i into the bore m of the drill. The agent, *e. g.*, compressed air, for operating on the flushing water, is introduced 25 into the chamber A preferably with an undiminished pressure and in an uninterrupted stream. The said agent then passes, through that annular portion of the outer pipe k which surrounds the pipe i , directly 30 into the bore m of the drill. As the pressure energy of the agent is partly converted into velocity energy when the said agent leaves the pipe, the flushing water issuing from the pipe i is ejected with greater force through 35 the bore of the drill. Moreover, as the pressure agent issues at a point behind the point of issue of the flushing water, there is continually formed a zone of compressed air of uniform pressure and of considerable jet- 40 action, which zone closes the rear opening into the bore m , and which, standing as a barrier to the jet of water, thus effectively prevents a leakage of the same into the interior of the machine. The flushing device 45 is kept completely independent of the operation of the pressure means within the machine proper, owing to the piston-rod d passing air-tight through the cover f . Moreover, owing to the bore in the piston opening into 50 the chamber C provided with the outlet n , there cannot occur in the chamber D a counter pressure in any way affecting the operation of the machine. Air under pressure always exists in the space D by reason of the 55 zone of compressed air which closes the rear opening of the bore m .

The second form of flushing device illustrated in Fig. 2 has the advantage of shorter length owing to the piston-rod d being excluded. In order in every case to obtain a sufficient jet-action of the flushing mixture in the bore of the drill it is possible, owing to the compressed air and water being separately introduced, to obtain in the bore of 60 the drill an exact regulation both of pressure

and of the admitted quantities of compressed air and water before these enter the pipes i and k .

I claim:—

1. A percussion machine drill, comprising a casing, a hollow drill at one end of the same, a piston guided longitudinally in the casing to and from the drill, a water supply pipe terminating within the drill, means for supplying water to said water supply pipe at a pressure less than the flushing pressure, and a supply pipe for compressed air terminating within the drill, the said terminal of the said compressed air pipe being intermediate the terminal of the water supply pipe and the piston, the said compressed air driving said water into said drill at the flushing pressure. 70

2. A percussion machine-drill, comprising a casing, a hollow drill at one end of the same, a hollow piston guided longitudinally in the casing to and from the drill, a water supply pipe extending axially through the piston and terminating within the drill, and a compressed air pipe likewise extending axially through said piston and terminating in said space, the water pipe being co-axial with and arranged within the air pipe, said water pipe being connected at its rear end with the casing and said air pipe being connected at its rear end with the casing air tight from said water pipe. 80

3. A percussion machine-drill, comprising a hollow casing, a hollow drill at one end of the same, a cover at the other end, means for delivering a continuous stream of water under pressure in drilling direction at the longitudinal axis of the machine, a piston guided longitudinally in the casing to and from the drill, and having at its rear end a piston rod guided air tight in said cover, said water delivering means terminating within the drill, and means for delivering a continuous stream of compressed air in the same space in drilling direction at the longitudinal axis of the machine. 100

4. A percussion machine-drill comprising a hollow casing, a hollow drill at one end of the same, a piston guided longitudinally in the casing to and from the drill, a water supply pipe extending axially through the piston and terminating within the drill, and a compressed air pipe likewise extending axially through said piston and terminating in said space, said piston having a bore of larger diameter than said pipes therein, and said casing having behind the piston an outlet communicating with said bore. 115

5. A percussion machine drill, comprising a casing, a hollow drill at one end of the same, a piston guided longitudinally in the casing to and from the drill, a water supply pipe terminating within the drill, and a supply pipe for compressed air terminating within the drill and connected to 120

said casing away from the terminal of said water supply pipe, and a connecting pipe between the terminal of the said compressed air supply pipe and the space between the 5 said drill and the said piston.

In testimony, that I claim the foregoing

as my invention, I have signed my name in presence of two subscribing witnesses.
